FIG - 1

FIG - 2

To all whom it may concern:

Be it known that I, Karl Kipp, a citizen of the United States, residing at Olean, in the county of Cattaraugus and State of New York, have invented a new, original, and ornamental Design for a Stool or Similar Article, of which the following is a specification, reference being had to the accompanying drawing, forming part thereof, and in which:

Fig. 1 is a perspective view of a stool or similar article showing my new design; and

Fig. 2 is a side elevational view thereof.

The characteristic features of the design reside in the portions shown in full lines.

I claim:

The ornamental design for a stool or similar article, substantially as shown and described.
